MODULAR MANIFOLD BLOCK

Henry William Demler, Sr., Lebanon, Pa., assignor to AMP Incorporated, Harrisburg, Pa.

Filed June 23, 1965, Ser. No. 85,862

Term of patent 14 years

(Cl. D78—1)

I claim:

The ornamental design for a modular manifold block, as shown and described.
